CLAIM

The ornamental design for a breastshield for a breastpump, as shown and described.

DESCRIPTION

FIG. 1 is a perspective view of a breastshield for a breastpump according to the present invention;

FIG. 2 is a second perspective view of the present invention as illustrated in FIG. 1;

FIG. 3 is a third perspective view of the present invention as illustrated in FIG. 1;

FIG. 4 is a right side view of the present invention as illustrated in FIG. 1, the left side view being identical;

FIG. 5 is a front view of the present invention as illustrated in FIG. 1, the back view being identical;

FIG. 6 is a top view of the present invention as illustrated in FIG. 1; and,

FIG. 7 is a bottom view of the present invention as illustrated in FIG. 1.
